(57) **CLAIM**

The ornamental design for a container lid with handle, as shown and described.

DESCRIPTION

FIG. 1 is a top, rear, left perspective view of a first embodiment of a container lid with handle, showing my new design;

FIG. 2 is a top, rear, right perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view of the container lid with handle as shown in FIGS. 1-7 which shows the container lid with handle in a closed configuration.

FIG. 9 is a left side elevation view of the container lid with handle of FIG. 1, shown in a partially open configuration for clarity of disclosure;

FIG. 10 is a top plan view of the container lid with handle of FIG. 1, shown in a fully open configuration for clarity of disclosure;

FIG. 11 is a top, rear, left perspective view of a second embodiment of a container lid with handle; and,

FIG. 12 is a top plan view thereof.

The broken lines in the drawings depict portions of the container lid with handle that form no part of the claimed design.
